[57] **CLAIM**

The ornamental design for a golf tee, as shown.

DESCRIPTION

FIG. 1 is a perspective view of a golf tee showing my new design;

FIG. 2 is a side elevation view thereof;

FIG. 3 is a side elevation view thereof opposite to that shown in FIG. 2;

FIG. 4 is a top plan view thereof;

FIG. 5 is a front elevation view thereof;

FIG. 6 is a bottom plan view thereof; and

FIG. 7 is a rear elevation view thereof.
